CLAIM

The ornamental design for a flashlight, as shown and described.

DESCRIPTION

FIG. 1 is a perspective view of a flashlight according to the first embodiment of the invention.

FIG. 2 is a front elevational view of a flashlight according to the first embodiment of the invention.

FIG. 3 is a rear elevational view of a flashlight according to the first embodiment of the invention.

FIG. 4 is a left side elevational view of a flashlight according to the first embodiment of the invention.

FIG. 5 is a top plan view of a flashlight according to the first embodiment of the invention.

FIG. 6 is the perspective view from another angle of a flashlight according to the first embodiment of the invention.

FIG. 7 is a perspective view of a flashlight according to the second embodiment of the invention.

FIG. 8 is a front elevational view of a flashlight according to the second embodiment of the invention.

FIG. 9 is a rear elevational view of a flashlight according to the second embodiment of the invention.

FIG. 10 is a left side elevational view of a flashlight according to the second embodiment of the invention.

FIG. 11 is a top plan view of a flashlight according to the second embodiment of the invention; and,

FIG. 12 is the perspective view from another angle of a flashlight according to the second embodiment of the invention.
